UNITED STATES PATENT OFFICE.

CHARLES S. RICHMAN AND ERNEST OTTO FECHNER, OF SAN FRANCISCO, CALIFORNIA.

TURBINE-FLUE CLEANER.

Application filed April 4, 1922. Serial No. 549,551.

To all whom it may concern:

Be it known that we, CHARLES S. RICHMAN, a citizen of the United States, and ERNEST OTTO FECHNER, a citizen of Germany, residing at San Francisco, in the county of San Francisco, State of California, have invented a new and useful Turbine-Flue Cleaner, of which the following is a specification in such full and clear terms as will enable those skilled in the art to construct and use the same.

This invention relates to a fluid pressure turbine and an object of the invention is to produce a turbine capable of operating any desired rotor apparatus to convert fluid pressure into motion.

Another object of the invention is to produce a fluid pressure turbine which will have more reacting blades in a given space than many forms of turbines and which will be so shaped as to enable the steam fluid used to pass outwardly from the rotor to a shell like stator and then inwardly to the rotor again escaping therefrom at the end whereby the number of moving parts of the engine is considerably reduced.

Other objects of the invention will appear as the description proceeds.

An embodiment of the invention is shown in the accompanying drawings in which the same reference numeral is applied to the same portion throughout, but we are aware that there may be modifications thereof.

Fig. 1 is a side elevation of the turbine showing a flue cleaner applied to the same.

Fig. 2 is an end elevation of the turbine showing the flue cleaner thereon.

Fig. 3 is a bottom plan view of the turbine.

Fig. 4 is a vertical sectional view of the turbine, the driven apparatus being omitted therefrom.

Fig. 5 is a transverse sectional view on the line 5—5 Figure 4.

Figures 6 and 7 are transverse sectional views on the plane 6—6 and 7—7 respectively Figure 4.

Fig. 8 is a side elevation of the rotor.

Fig. 9 is a side elevation of the stator cage.

Figures 10, 11, 12 and 13 are each horizontal sectional views on the lines 10—10, 11—11, 12—12 and 13—13 Figure 4 looking in the direction of the respective arm rows.

The turbine is mounted on the end of the

steam supply pipe 1, which pipe has a threaded bushing 2 to connect it with the bell end 3. In order to turn the bell 3 without injuring the same it is provided with a series of four holes 4 and a special wrench is used thereon to tighten it on the bushing 2. The opposite end of the bell is connected to a cylindrical shell 5 by means of threads, and this shell has the shaft bearing 6 secured thereto at its outer end. The shell is also flanged inwardly as seen at 7 to retain the stator cage 8.

The rotor shaft 9 passes through the bearing 6 which is a split bearing having the removable part 10 and into a bushing 11 held in the plate 12. A plug 13 is used to close the opening in the end of the bushing 11 and to retain lubricant therein.

The plate 12 exactly fits the inside of the outer shell 5 and it has a plurality of inclined passageways therethrough as illustrated at 13 and 14 in Figures 11 and 13. The plate 12 is held in a fixed position by the cage 8, and said cage has two series of inclined peripheral openings 15 and 16. These openings are connected on the outside of the cage by slots 17 somewhat wider than the slots 15 and 16 but which slots 17 do not extend entirely through the cage so that an opening is produced on the outer periphery of the cage from each slot 15 to each other slot 16.

The rotor 18 consists of a solid head provided with three packing rings 19, 20 and 21 and it is provided with inclined slots 22 extending from one end toward the middle of the rotor and tapering out at the periphery. At the other end there are a plurality of slots 23 which are in exactly the reverse position from the slots 22 beginning at a point near the center piston ring 20 and extending deeper toward the end of the rotor at which point they terminate in elongated slots as indicated in Figure 5.

Under the bearing 6 there is a fixed plate 24, while the shaft 9 carrying the rotor has a fixed plate 25 secured thereto to act as wear plates for the thrust bearing cage 26.

The rotor is held in place on the shaft 9 by means of the nut 27.

The head for cleaning the tubes comprises a heavy shaft 30 with two three-armed spiders 31, 32. Each spider arm is provided with a radially extending slot as indicated at 33 and through each pair of these slots there extends a shaft 34, each of said shafts

- extending into a bearing cup 35 at one end and into a tubular bearing 36 at the other end. The bearings 35, 36 are flanged so that when once placed in position and with the cutters 37 and spacers 38 assembled on the pin 34 they cannot escape and can only move radially along the slots in which they are placed. Cotter pins 39 are used to prevent the pin 34 from dropping out of place.
- 10 The cutters 37 consist of hardened toothed discs separated by suitable washers to give the necessary clearance to knock off the lime accumulation from the inside of the boiler flue.
- 15 The operation of the apparatus is as follows: Assuming steam or air to be supplied to the cleaner through the tube 1, the steam first passes through the plate 12 in a direction at an inclination to the axis of the shaft 9. It then strikes the openings in the ends of the rotor from which it passes through the rotor peripherally into the slots in the cage 8. It then passes through the slot 17 and back into the rotor above the piston ring 20, thereafter passing out the end of the rotor and escapes therefrom through the inclined slots in the inwardly projecting flange 7.
- Each pair of slots is arranged with respect to each other in a manner well known in the construction of turbines to give the greatest reactive effect to the moving steam.
- 20 It will also be clear that if it is desired the cage 8 might have two or more pairs of slots in which event the rotor itself would have pairs of slots to correspond with the pairs of slots in the cage.
- 25 During the rotation of the rotor the cutter carriers will be thrown violently outward by the centrifugal motion and will thereby

chop off any scale collected on the inside of 40 the boiler flue.

What we claim is as follows, but various modifications may be made in the construction shown in the drawings and above particularly described form, within the purview 45 of our invention.

1. A turbine for boiler flue cleaners comprising a stator having two series of inclined slots with passageways extending from one slot to another of the series, and a rotor having two series of slots, said rotor fitting the stator whereby steam will pass from one end of the rotor out through the same into the stator and then back into the rotor to drive the same.

2. In a turbine the combination of a slotted casing with a rotor having two series of slots formed therein, the arrangement of slots being such that steam passing to the rotor will pass into the end of the rotor then through its periphery and then back into the rotor through its periphery at another portion thereof and be discharged from the rotor at the end of the same.

3. In a turbine the combination of a casing having a plurality of inclined slots therein, and a rotor closely fitting said casing, said rotor having a plurality of inclined slots arranged to allow the entrance of fluid at the end of the rotor discharging the same through its periphery and then permitting it to re-enter the periphery of the rotor and finally escape at the end of the rotor.

In testimony whereof we have hereunto set our hands this 23rd day of March, A. D. 1922.

ERNEST OTTO FECHNER.
CHARLES S. RICHMAN.
